(57) **CLAIM**

I claim the ornamental design for a golf club grip, as shown and described.

DESCRIPTION

FIG. 1 is a first perspective view of a golf club grip showing my new design;

FIG. 2 is a second perspective view thereof;

FIG. 3 is a top view thereof;

FIG. 4 is a bottom view thereof;

FIG. 5 is a right-side view thereof;

FIG. 6 is a left-side view thereof;

FIG. 7 is a front view thereof;

FIG. 8 is a back view thereof;

FIG. 9 is a first perspective view thereof showing indeterminate dimensions;

FIG. 10 is a second perspective view thereof showing indeterminate dimensions;

FIG. 11 is a top view thereof;

FIG. 12 is a bottom view thereof;

FIG. 13 is a right-side view thereof;

FIG. 14 is a left-side view thereof;

FIG. 15 is a front view thereof; and,

FIG. 16 is a back view thereof.

The broken lines depicting part of a shaft and club head in FIGS. 1 and 9 are for the purpose of illustrating environmental structure and form no part of the claimed design. The broken lines depicting an exemplary air vent in FIGS. 1, 2, 3, and 4 form no part of the claimed design.

The broken away symbols in FIGS. 9-16 indicate the appearance of any portion of the article between the break lines forms no part of the claimed design.

1 Claim, 10 Drawing Sheets
